UNITED STATES PATENT OFFICE.

CHARLES W. BECK, OF DETROIT, MICHIGAN, ASSIGNOR TO THE BECK-FROST CORPORATION, A CORPORATION OF MICHIGAN.

TERMINAL.

1,268,812.

Specification of Letters Patent. Patented June 11, 1918.

Application filed January 4, 1915. Serial No. 432.

To all whom it may concern:

Be it known that I, CHARLES W. BECK, a citizen of the United States of America, residing at Detroit, in the county of Wayne 5 and State of Michigan, have invented certain new and useful Improvements in Terminals, of which the following is a specification, reference being had therein to the accompanying drawings.

10 The invention relates to electrical terminals, and consists in the provision of a simple and efficient terminal that may be easily and quickly attached to or detached from a binding post or other member; in a construction of terminal that may be employed for engaging binding posts or other members of various sizes, and which—when attached to the binding post or the like—will be secured thereto against accidental disengagement; in the provision of a terminal that may be readily engaged with an electrical conduit; and further, in a construction of coupler that may be easily and cheaply manufactured. The invention further relates 15 in certain constructions, arrangements and combinations of parts as will more fully hereinafter appear.

In the drawings,—

Figure 1 is a perspective view of a terminal embodying the invention;

Fig. 2 is a front elevation showing the terminal applied to a binding post;

Fig. 3 is a longitudinal, sectional view through the structure of Fig. 2;

Fig. 4 illustrates a blank from which a part of the terminal is made; and

Fig. 5 shows the manner of attaching the terminal to the conduit and binding post.

Referring to the one embodiment of the invention shown in the drawing, A designates the improved terminal composed of a member B formed of suitable metal and a clamping sleeve C made of insulating material. In the structure illustrated the member B is provided with coöperating segmental portions D and E, forming in effect when engaged with the conduit, a split shank. The portions D and E are provided with threads which are engaged by the internal threads of the sleeve C, as shown in Fig. 3.

50 The latter is preferably slightly tapered so that upon adjustment of the sleeve C the portions D and E will be tightly clamped against the insulation of the electrical conduit F. G is the wire of the conduit F

which engages a struck-up bearing portion H on the part D. The bearing H is such as to allow the end of the wire G to be inserted from the forward side thereof and then bent over the top of the bearing H, as 60 shown in Fig. 3. The wire may then be soldered in place if desired. The member B is provided with a wide, flat portion J which—when the terminal is assembled—forms an eye for engaging the binding post K or other 65 member to which the terminal is to be attached. If the binding post K is provided with threads, the portion J may also be provided with threads complementary to the threads of the binding post. 70

By the arrangement just described, the member B may be stamped from a flat blank of metal into the form shown in Fig. 4. When it is desired to apply the terminal to an electrical conduit, the sleeve C is first engaged with the conduit, then the wire of the electrical conduit is connected to the bearing H, as heretofore described, and the members B bent around the binding post until the portions D and E are both in engagement with the conduit F, as shown in dotted lines in Fig. 5. The sleeve C is then moved into engagement with the threads of the portions D and E. Upon screwing the sleeve upon the portions D and E the latter 85 will be tightly clamped to the insulation of the conduit, and also the eye J will be clamped to the binding post.

From the foregoing description it will be readily apparent that the terminal is one 90 that may be easily and cheaply manufactured, and that may be readily attached to or detached from an electrical conduit. Furthermore the terminal is clamped to the conduit and also to the binding post by the 95 same operation.

While I have shown and described the preferred form of the invention, I do not wish to limit my protection to the particular structure illustrated, and also while I 100 have shown the terminal as adapted for engaging a binding post, it may be constructed for engaging other members.

What I claim as my invention is:

1. A terminal comprising a blank bent 105 into substantially U-shaped form, the legs of the U having segmental portions for engaging the insulator covering of a wire and one of the legs having a struck-up bearing portion for engaging said wire, the base of 110

the U forming a bearing for engaging a terminal or the like, and a sleeve engaging said segmental portions.

2. A terminal adapted to be connected to an electrical conduit, comprising a blank bent into substantially U-shaped form, the legs of the U having segmental portions for engaging said conduit and one of the legs having a struck-up bearing portion for engaging the end portion of said conduit, the

base of the U forming a bearing for engaging a terminal or the like, and means for clamping said segmental portions of the leg upon said conduit.

In testimony whereof I affix my signature 15 in presence of two witnesses.

CHARLES W. BECK.
